CONTROL DEVICE

Philip R. Marvin, Bloomington, Ind., assignor to Milwaukee Gas Specialty Company, Milwaukee, Wis., a corporation of Wisconsin

Application May 24, 1951, Serial No. 228,063

8 Claims. (Cl. 158—28)

This invention relates, in general, to control devices, and has particular relation to an improved valve for controlling the supply of liquid fuel to a stove or other burner for heating, for example, a tent or other portable shelter or the like.

One of the main objects of the present invention is to provide for supplying an initial measured priming charge or "shot" of gasoline or other liquid fuel to the burner for starting.

Another object of the invention is to provide for thereafter supplying fuel to the burner for heating purposes.

Another object of the invention is to provide in a device of the character described a thermoelectric safety shut-off, and, more specifically, a thermoelectric safety shut-off with flow interrupter means for interrupting the flow of fuel during the operation of resetting the thermoelectric safety shut-off; also upon extinguishment of the burner.

Another object of the invention is to provide a device of the character described having features and advantages set forth and provided with improved means for regulating the flow of fuel to the burner.

Another object of the invention is to provide, in a device of the character described, a valve body, and means defining a passageway and comprising a valve seat member and a valve closure member cooperating in first positions of the members to close the passageway and with the valve seat and closure members having movement from their first positions to second positions with the members in cooperation to close the passageway during such movement.

Another object of the invention is to provide means, and, more particularly, an armature and an electromagnet connected in circuit with a thermoelectric generator for holding one of the valve seat and closure members in its second position, and means for returning the other member to its first position to separate it from the cooperating member when said member is held in its second position whereby to open the passageway.

Another object of the invention is to provide a device of the character described wherein the valve body has an inlet and an outlet, and wherein there is means defining a fluid-receiving cavity positioned in the first positions of the valve seat and closure members to receive a measured charge of fluid from the inlet and which cavity is positioned in the second positions of the valve seat and closure members out of communication with the inlet and in communication with the outlet for discharging the measured charge of fluid through the outlet.

Another object of the invention is to provide a device of the character described wherein the passageway communicates with the outlet for the flow of fluid from the inlet to the outlet when the valve seat and closure members are separated.

Another object of the invention is to provide in a device of the character described, means for venting entrapped air from the fluid receiving cavity.

Further features and advantages and numerous adapta-

tions of the invention will be apparent from the following detailed description and the accompanying drawing in which the single figure is an axial sectional view through a control device embodying the present invention; also showing diagrammatically a connected burner, a gravity fuel feed for the burner, and a thermoelectric generator connected in circuit with the electromagnet of the control device and positioned where it is responsive to the heat of the burner.

Referring now to the drawing, the embodiment of the invention selected for illustration comprises a tubular valve body 1 having a fuel inlet 2 and a fuel outlet 3.

In the particular device selected for illustration, the valve is gravity fed from a liquid fuel tank 4, disposed at a higher level by a fuel supply pipe 5. A fuel supply pipe 6 leads to the burner 7 from the outlet 3 for the delivery of liquid fuel to the burner. The burner 7 may be the burner of a stove for heating, for example, a tent or other portable shelter, or it may be any other suitable burner.

A plunger 8 is mounted for reciprocatory sliding movement in the interior of the body 1, and is provided within its length with a reduced portion forming an annular liquid fuel receiving cavity 9. The plunger 8 has a first position as shown in the drawing, with the cavity 9 in communication with a port 10 opening from the inlet 2 to receive a measured priming charge or "shot" of liquid fuel, and is movable inwardly to a second position with the cavity 9 out of communication with the inlet port 10, and in communication with an outlet port 11 which opens into the outlet 3 for delivering the measured charge of fuel to the burner 7.

Before cavity 9 can be filled with fuel, the air must be allowed to escape therefrom. For this purpose a hollow fitting 12 is screwed, at 13, into the valve body 1 in position so that its inner end will open from the cavity 9 when the plunger 8 is in the position shown in the drawing. A valve stem 14 has reciprocatory movement in an axial opening 15 in the fitting 12. The inner end of the stem 14 carries a valve member 16 which is seated against a valve seat 17 by a spring 18 coiled about the outer end of the stem 14 and acting between the outer end of the fitting 12 and a cup-shaped knob 19 attached, for example, by a screw 20 to the outer end of the stem 14. A vent opening 21 opens outwardly from the space 22 formed by reducing the cross-section of the adjacent portion of the stem 14.

Sealing rings 23 and 24 are mounted in annular grooves in the periphery of the plunger 8, one beyond each of the opposite ends of the cavity 9 to seal the device against flow or leakage of liquid fuel along the cooperating surfaces of the plunger 8 and valve body 1. The rings 23 and 24 are preferably formed of material having suitable resistance to the liquid fuel employed.

The plunger 8 has a port 25 which opens from the cavity 9 into an axial passageway 26 in the plunger. A valve seat member 27 is mounted in the inner end of the plunger 8 and has a passageway 28 coaxial with the passageway 26 and forming a continuation thereof, as will presently appear. The enlarged outer end of the valve seat member 27 is counterbored at 29 to receive the tapered end of a valve closure member 30 which cooperates with an annular valve seat 31 in the valve seat member 27 to close the passageway 26, 28.

The valve closure member 30 is attached at 32 to a stem 33. An armature 34 is mounted on the opposite end of the stem 33 for movement to attracted and retracted positions relative to the pole ends of the magnet frame 35 of an electromagnet 36 with accompanying rectilinear movement of stem 33 and valve closure member 30, as will presently appear. The attachment of the armature 34 to the stem 33 is preferably of a character to permit self-

accommodation of the armature to the pole faces of the magnet frame 35 when the armature is in attracted position.

Screwed or otherwise secured in one end of the valve body 1 is a magnet mounting nut 38. The electromagnet 36 is enclosed within an inner shell 39 and comprises the magnet frame 35 secured, for example, to a terminal bushing 40. A coil is provided at 41. The bushing 40 is clamped in place, for example, by a nut 42 and has a threaded opening for receiving an attaching nut 43 of a thermoelectric generator lead. The lead comprises line conductors 44 and 45 which may be concentric or of other suitable form, connected in circuit at one end with the thermoelectric generator elements 46 and 47 of the thermoelectric generator 48. The elements 46 and 47 are joined at 49 to form the "hot" junction which is heated by the flame of the burner 7. The opposite end of the lead conductor 45 has a connector cone 50 which is clamped in contact with a terminal tip 51 by the nut 43. The other conductor 44 is connected in circuit with one side of the coil 41, and the other side of the coil is connected to the lead conductor 45 through the terminal tip 40.

While the thermoelectric generator 48 is shown in the form of a thermocouple, it may be in the form of a thermopile or of any other suitable form.

A needle valve 54 extends axially through the passageway 26 with an annular space between it and the passageway. The needle valve 54 has a tapered inner end which is adjustably cooperable with the adjacent end of the passageway 28 and the stem of the needle valve has adjustable screwed engagement at 55 with the plunger 8, and has attached to its outer end, at 56, a starting knob 56. The position of the tapered inner end of the needle valve 54 is adjusted by turning the knob 56 to control the rate of flow of fuel to the burner. In one illustrative embodiment of the invention, a flow rate of 0 to about $\frac{1}{2}$ gallon of liquid fuel per hour is satisfactory. The knob 56 encloses a gland nut 58 which is screwed in the end of the valve body 1 and compresses packing 59 about the adjacent portion of the needle valve stem 54.

A coiled spring 60 is interposed between the inner end of the shell 39 and an abutment disc 61 on the stem 33 and acts to move the closure member 30 to closed position against the valve seat 31 when the armature 34 is released from the electromagnet 36. Another coiled spring 63 is interposed between the inner end of the shell 39 and the inner end of the plunger 8, and acts to return the plunger to the position shown in the drawing when it is released after being pressed inwardly to perform the starting operation. A screw 64 is screwed through the wall of the valve body 1 and has an inner end 65 which engages in a longitudinally extending groove 66 in the valve body 1 to prevent turning of the plunger 8 in the valve body.

The operation of the device is as follows:

With the plunger 8 in the position shown in the drawing, the knob 19 is pressed inwardly, thus opening the passage around the valve 16 and the annular space 22. This permits entrapped air to escape from cavity 9 through the vent opening 21. Assuming that the pipe 5 is open where, for example, there is a valve (not shown) in this pipe, gasoline or other liquid fuel is admitted to the cavity 9 and fills the same to provide a measured starting charge of fuel in the cavity 9. When knob 19 is released, the spring 18 causes the valve 16 to close.

Now when the knob 56 is pushed inwardly, it moves the plunger 8 from the first position shown in the drawing to a second position, with the cavity 9 out of communication with the inlet port 10 and in communication with the outlet port 11. The plunger 8 then has discharge relation with the outlet port 11, and the measured amount of fuel is delivered to the burner 7 for starting the same. The burner 7 may be ignited with a match, taper, or otherwise as desired, and heats the "hot" junction or junctions of the thermoelectric generator 48.

When the knob 56 is pressed inwardly, the valve seat 31

is in engagement with the valve closure member 30, thereby closing the passageway 26, 28 against the flow of fuel therethrough. The engagement of the valve seat 31 with valve closure member 30 moves the armature 34 to attracted position relative to the magnet frame 35 with the inward movement of knob 56.

When the thermoelectric generator 48 has been heated by the burning of the initial or priming charge of fuel, the electromagnet 36 is energized and holds the armature 34 in attracted position and the valve closure member 30 against following the valve seat 31 in the return movement of the plunger 8 to the position shown in the drawing when the knob 56 is released. When the armature 34 is held in attracted position, the knob 56 is released. This release of the knob 56 allows spring 63 to return the plunger 8 to the position shown in the drawing, thus uncovering inlet port 10 so that the cavity 9 may receive the succeeding measured charge of fuel for priming the burner.

When the plunger 8 returns to the position shown in the drawing, with the armature 34 held in attracted position and valve closure member 30 held against following the plunger 8, the valve seat 31 separates from the valve closure member, thus opening the passageway 26, 28.

Fuel may now flow through port 10, cavity 9, port 25, passageways 26, 28, the interior of valve body 1 to the left of the inner end of the plunger 8 as the device is shown in the drawing, and out through an outlet port 70 and outlet 3 to the burner 7. As previously set forth, turning of the knob 56 turns the needle valve stem 54 to adjust the position of its tapered end relative to the valve seat at the adjacent end of the passageway 28 to control the rate of flow of fuel to the burner.

In case of flame failure, the "hot" junction or junctions of the thermoelectric generator cool, the electromagnet 36 is deenergized or its energization reduced, and spring 60 closes valve 30. This stops or shuts off the flow of fuel to the burner.

The embodiment of the invention shown in the drawing is for illustrative purposes only, and it is to be expressly understood that said drawing and the accompanying specification are not to be construed as a definition of the limits or scope of the invention, reference being had to the appended claims for that purpose.

I claim:

1. A control device for controlling flow of fluid comprising a valve body having a fluid inlet and a fluid outlet, a first member biased to retracted position in said valve body and movable to a second position, means for holding said first member in said second position, a second member biased to released position in said valve body and movable to a second position, said first member when in retracted position coacting with said second member for movement of said first member to its second position by movement of said second member to its second position, said second member having a fluid receiving cavity positioned in register with said inlet when said second member is in its released position and movable out of register with said inlet and into register with said outlet by movement of said second member to its second position, said second member having a passageway placing said inlet in communication with said outlet when said first member is held in its second position and said second member returns to its released position, and valve means shutting off communication between said inlet and said outlet through said passageway when said first member is in position coacting with said second member.

2. A control device for controlling flow of fluid comprising a valve body having a fluid inlet and a fluid outlet, a first member biased to retracted position in said valve body and movable to a second position, means for holding said first member in said second position, a second member biased to released position in said valve body and movable to a second position, said first member when in retracted position coacting with said second member for movement

of said first member to its second position by movement of said second member to its second position, said second member having a fluid receiving cavity positioned in register with said inlet when said second member is in its released position and movable out of register with said inlet and into register with said outlet by movement of said second member to its second position, said second member having a passageway placing said inlet in communication with said outlet when said first member is held in its second position and said second member returns to its released position, valve means shutting off communication between said inlet and said outlet through said passageway when said first member is in position coacting with said second member, and means for venting entrapped air from said fluid receiving cavity.

3. A control device for controlling flow of fluid comprising a valve body having a fluid inlet and a fluid outlet, a first member biased to retracted position in said valve body and movable to a second position, means for holding said first member in said second position, a second member in the form of a plunger having sliding movement in said valve body and biased to released position in said valve body and movable to a second position, said first member when in retracted position coacting with said plunger for movement of said first member to its second position by movement of said plunger to its second position, said plunger having a fluid receiving cavity formed by an annular groove opening from the outer periphery of the plunger with plunger portions on opposite ends of said groove in sliding and sealed cooperation with the inner periphery of said valve body, said fluid receiving cavity being positioned in register with said inlet when said plunger is in its released position and movable out of register with said inlet and into register with said outlet by movement of said plunger to its second position, said plunger having a passageway placing said inlet in communication with said outlet when said first member is held in its second position and said plunger returns to its released position, and valve means shutting off communication between said inlet and said outlet through said passageway when said first member is in the position coacting with said plunger.

4. A control device for controlling flow of fluid comprising a valve body having a fluid inlet and a fluid outlet, a first member biased to retracted position in said valve body and movable to a second position, means for holding said first member in said second position, a second member in the form of a plunger having sliding movement in said valve body and biased to released position in said valve body and movable to a second position, said first member when in retracted position coacting with said plunger for movement of said first member to its second position by movement of said plunger to its second position, said plunger having a fluid receiving cavity formed by an annular groove opening from the outer periphery of the plunger with plunger portions on opposite ends of said groove in sliding and sealed cooperation with the inner periphery of said valve body, said fluid receiving cavity being positioned in register with said inlet when said plunger is in its released position and movable out of register with said inlet and into register with said outlet by movement of said plunger to its second position, said plunger having a passageway placing said inlet in communication with said outlet when said first member is held in its second position and said second member returns to its released position, valve means shutting off communication between said inlet and said outlet through said passageway when said first member is in position coacting with said plunger, and an adjusting stem adjustable in said plunger for adjusting the rate of fluid flow through said passageway.

5. A control device for fluid fuel burning apparatus having a burner comprising an armature movable to attracted and retracted positions, an electromagnet adapted when energized to hold said armature in attracted position,

70
75

a thermoelectric generator connected in circuit with said electromagnet and adapted when heated to energize said electromagnet, reset means movable in resetting direction to reset said armature into attracted position and movable to released position, a movable member having a cavity for receiving a measured priming charge of fuel when said reset means is in released position and movable with said reset means to deliver said measured priming charge to said burner by movement of said reset means in resetting direction, said device also including means for delivering a running supply of fuel to said burner but only when said armature is held in attracted position and said reset means returns to released position, and means operable to shut off the running supply of fuel for said burner by movement of said armature to retracted position.

6. A control device according to claim 5 wherein the means operable to shut off the running supply of fuel to said burner by movement of said armature to retracted position also operates to shut off said running supply of fuel for said burner during resetting movement of said reset means and until said armature is held in attracted position by said electromagnet and said reset means returns to released position.

7. A control device for fluid fuel burning apparatus having a burner comprising a valve body having a fluid fuel inlet and a fluid fuel outlet, a first member biased to retracted position and movable to attracted position, an electromagnet adapted when energized to hold said first member in attracted position and when deenergized to release said first member for movement to retracted position, a thermoelectric generator adapted to be heated by said burner and connected in circuit with said electromagnet to energize the same as long as the thermoelectric generator is heated by the burner flame, a second member biased to released position in said valve body and movable to a second position, said first member when in retracted position coacting with said second member for movement of said first member to its attracted position by movement of said second member to its second position, said second member having a fluid fuel receiving cavity positioned in register with said inlet to receive a priming charge of fuel for said burner when said second burner is in released position and movable out of register with said inlet and into register with said outlet for delivering the priming charge of fuel to said outlet by movement of said second member to its second position, said second member having a passageway placing said inlet in communication with said outlet for delivery for a running supply of fuel for said burner when said first member is held in its second position and said second member returns to released position, and valve means shutting off communication between said inlet and said outlet through said passageway when said first member is in position coacting with said second member.

8. A control device according to claim 7 wherein said second member is in the form of a plunger with enlarged plunger portions having sealed sliding cooperation with the inner periphery of said valve body and spaced to form an annular cavity therebetween for receiving the priming charge of fuel, and means for venting entrapped air from said cavity.
